UNITED STATES PATENT OFFICE

BRUNO RADTKE, OF LIBERTYVILLE, ILLINOIS, ASSIGNOR TO MILLS NOVELTY COMPANY, OF CHICAGO, ILLINOIS, A CORPORATION OF ILLINOIS

SELF-PLAYING STRINGED INSTRUMENT

Application filed March 8, 1928. Serial No. 259,994.

This invention relates to self-playing musical instruments, and more particularly to string instruments which are adapted to be played by means of mechanical fingering devices and bows under electric control. In instruments of this character, the strings have a vibratory motion, particularly when the instrument is equipped with devices for producing a tremolo effect by rapidly increasing and decreasing the tension on the strings, thus causing longitudinal movement thereof. This is perhaps particularly true in the case of the automatic cello, in connection with which my invention is illustrated in the accompanying drawings.

With the fingering devices heretofore employed, this vibratory movement of the strings has caused the same to slip with respect to the fingering devices, thus interfering with the effectiveness of the latter by causing the grip thereof on the strings to be lessened.

The principal object of the present invention is to provide, in a self-playing string instrument, a fingering device which is so constructed that the string-engaging element will retain its grip upon or contact with the string, notwithstanding vibratory movements of the latter.

Other objects and advantages of the invention will be apparent as it is better understood from the following description, which, taken in connection with the accompanying drawings, discloses a preferred embodiment thereof.

Referring to the drawings,

Figure 1 is a side elevational view of a self-playing cello in which my invention is embodied;

Fig. 2 is a transverse sectional view, taken substantially on the section line 2-2 of Fig. 1;

Fig. 3 is a partial longitudinal section, taken substantially on the section line 3-3 in

Fig. 2; and

Fig. 4 is a plan view, showing a portion of the neck of the cello and the arrangement of the fingering devices with respect to the strings.

Upon said drawings, illustrating the pre-

ferred embodiment of my invention, the reference character 21 indicates a cello, adjustably supported in a frame comprising a base 22, to which a threaded rod 23 is pivotally secured at one end, as indicated at 24, said rod carrying a bracket 25, having a supporting arm 26 and equipped with a lug 27, to which a projection 28 on the cello is pivotally attached, as indicated at 29, an upright 31 being provided near the opposite end of the base 22 and being adapted to support the neck end of the cello, which is equipped with supporting arms 32, resting upon adjusting screws 33, carried in lateral projections 34 upon said upright 31.

The cello is adapted to be played in much the same manner as a self-playing violin of known type, such, for example, as that illustrated in United States Patent No. 807,871, dated December 19, 1905, and No. 855,021, dated May 28, 1907.

The strings 35, 36, 37, and 38 are fixedly secured at the lower end of the cello and extend over the usual bridge 39 and the neck 41 of the cello, the opposite ends of said strings being secured to tuning levers 42, having arcuate portions 43, pivotally secured at a knife-edge pivot point 43' to the frame and provided with lugs, or keepers, 44, said levers also being provided with hooks 45, to which the strings are secured, the shanks of said hooks being threaded, as indicated at 46, and adjustably held in lugs 47 on the tensioning lever 42 by means of nuts 48.

The desired spring tension is maintained upon the lever 42 by means of a spring 49, secured at one end to the lever 42 by means of a connection 51, and at the other end to a tensioning device 52 by means of a connection 53, said tensioning device being pivotally secured at 54 to a bracket 55 on a framepart 56 and being adapted to be adjusted by means of an adjusting screw 57.

A tremolo effect is produced by vibrating the levers 42 and the strings with which said levers are connected, the vibratory motion of said levers being produced by means of pistons (not shown) mounted in cylinders 58, supported upon the bracket 56 and connected by rods 59 with the levers 42, to which they

are attached at 61, a yielding connection being provided by means of springs 62.

The instrument is adapted to be played by means of rotating bows 63, carried upon shafts 64, driven by means of a power shaft 65, deriving its power from any suitable source, such as a motor (not shown), said shaft having bearings in a frame part 66 and a bracket 67, it being understood that a separate bow is provided for each string, the bow shaft being adapted to be depressed by means of electro-magnets 68, in well known manner.

The playing of the instrument is accomplished by a series of fingering devices operating in conjunction with the bows, said devices and the means for actuating the same being shown in detail in Fig. 2. Each finger comprises a body part 69, pivotally supported at 71 upon a side member 72 of a frame part 73, the fingers being normally held out of engagement with the strings by means of springs 74, secured to a hooked part 75 on the finger and to a projection 76 on a side plate 77 on the frame. Each finger is provided 25 with an enlargement, or head part 78 at the forward end thereof, in which there is formed a V-shaped notch 79, adapted to engage the string in manner which will be evident from viewing Fig. 2. The finger is split centrally 30 to provide upper and lower sections 81 and 82, the latter carrying the string-engaging part 78. The finger extends through slots in the plate 77 and in a plate 83, as indicated at 84 (see Fig. 3), and pieces of felt, or the like, 35 indicated at 85, are provided upon the upper section of the finger, over the part thereof which is depressed in the slot 84 of the plate 83, thus holding said section against movement in the longitudinal direction of the 40 strings. Similar felt pieces 86 are provided upon the finger and disposed within the slot in the plate 77 and at the forward end of the finger, as indicated at 87. The fingers are made of spring material and it will be evident 45 that the lower section 82 is permitted to have a vibratory movement with the strings, to the extent permitted by the width of the slot 84 in the plate 83 without imparting this motion to the upper section 81 of the finger. 50 This is a highly important advantage, since, if the string-engaging portion of the finger were held in fixed position, the vibratory motion of the strings, which in lengthwise direction, would produce a relative movement 55 with respect to the finger, thus interfering with the play and the efficiency of operation of the machine.

For the purpose of moving the fingers into and out of engagement with the strings, a series of solenoids 88 are provided, the same being mounted upon a pivoted head 89, shown clearly in Fig. 2, the same being pivotally secured at 91 to a frame part 92, the head being adapted to be secured in the down position by means of a bolt 93 and nut 94 (see

Fig. 2), the bolt extending through an arm 95 on the head 89 and a fixed frame part 96, the lower end of said arm 95 being slotted, as indicated at 97, to facilitate movement of the head to and from operative position.

A series of binding posts 98 is provided upon a side plate 99 secured to the head, said binding posts having connections 101 with the solenoids, in the usual manner. The head 89 carries four bars 102, supported by rods 103 at opposite ends of said head, the under sides of said bars being provided with felt, or other cushioning material, 104 adapted to contact with the upper ends of the cores 105 of the solenoids, the lower ends 106 of which are adapted to engage the forward ends of the upper sections of the fingers at the point where the felt covering 87 is provided.

The arrangement of the fingers will be understood from an inspection of Fig. 4, from which it will be apparent that said fingers are arranged in pairs, each comprising one relatively short, straight finger, indicated at 107 in said Fig. 4, and one elongated finger 108, the forward end of which is offset, as indicated at 109, so that the string-engaging portion thereof is arranged in line with the corresponding portion of the finger 107. The fingers shown at the left of Fig. 4 are of special formation, having padded disks 111 in place of the regular, notched string-engaging portions, said disks being for the purpose of stopping the vibration of the strings when desired. The remaining fingers are constructed as shown in Fig. 2 and arranged in pairs, as shown in Fig. 4 of the drawings.

When one of said solenoids 88 is energized, the core 105 thereof moves the associated finger downwardly, in obvious manner, into engagement with the string, and after the note has been played, the core is raised, permitting the finger to be turned upon its pivot by means of its spring 74, the finger thereupon assuming the position shown in Fig. 2. Obviously, if the finger were one solid piece, held tightly in engagement with the string, the vibratory motion of the latter would be interfered with, or would cause relative movement between the string and the finger, whereas, with the fingering devices constructed in accordance with the present invention, the string-engaging portion of the finger may move with the string during vibration of the latter, notwithstanding the pressure exerted upon the finger by the core of the actuating solenoid.

It is thought that the invention and many of its attendant advantages will be understood from the foregoing description, and it will be apparent that various changes may be made in the form, construction, and arrangement of the parts without departing from the spirit and scope of the invention, or sacrificing all of its material advantages, the

form hereinbefore described being merely a preferred embodiment thereof.

I claim:

1. In a self-playing stringed instrument, the combination of playing devices engageable with the strings, tremolo devices operable to produce endwise movement of the strings, and fingers movable into and out of engagement with the strings, said fingers having string-engaging portions movable with the strings to avoid slippage between said fingers and strings as the latter are moved longitudinally by said tremolo devices.
2. In a self-playing stringed instrument, the combination of playing devices engageable with the strings, tremolo devices operable to produce endwise movement of the strings, fingers movable into and out of engagement with the strings, said fingers being split to provide string-engaging portions movable with the strings and portions adapted to be held against movement with said strings, and actuating devices engaging said last-mentioned portions of the fingers.
3. In a self-playing stringed instrument, the combination of playing devices engageable with the strings, tremolo devices operable to produce endwise movement of the strings, fingers movable into and out of engagement with the strings, and devices engageable with said fingers for moving the same into engagement with the strings, each said finger comprising a split member one part of which is adapted to be engaged by one of said actuating devices and to be held against movement with the string and the other part of which is adapted to engage the string and to move therewith during the playing of the instrument.
4. In a self-playing stringed instrument, the combination of playing devices engageable with the strings, tremolo devices operable to produce endwise movement of the strings, fingers movable into and out of engagement with the strings, devices engageable with said fingers for moving the same into engagement with the strings, each said finger comprising a split member one part of which is adapted to be engaged by one of said actuating devices and to be held against movement with the string and the other part of which is adapted to engage the string and to move therewith during the playing of the instrument, and means for holding said first-mentioned part of the finger against movement with the string.
5. In a self-playing stringed instrument, the combination of playing devices engageable with the strings, tremolo devices operable to produce endwise movement of the strings, fingers movable into and out of engagement with the strings, devices engageable with said fingers for moving the same into engagement with the strings, each said finger comprising a split member one part

of which is adapted to be engaged by one of said actuating devices and to be held against movement with the string and the other part of which is adapted to engage the string and to move therewith during the playing of the instrument, and means for holding said first-mentioned part of the finger against movement with the string, said means comprising a slotted bracket in which the finger is movable toward and away from the strings and means upon the first-mentioned part of said finger whereby the same is held against transverse movement in said slot, the second-mentioned part of the finger having sufficient clearance in said slot to permit movement thereof with the string.

In witness whereof, I hereunto subscribe my name to this specification.

BRUNO RADTKE.
